[57] CLAIM

The ornamental design for a coin door, as shown and described.

DESCRIPTION

FIG. 1 is a front elevational view of the coin door according to my invention, with the door closed;

FIG. 2 is a rear elevational view thereof;

FIG. 3 is a top plan view thereof (view from below corresponds);

FIG. 4 is a left side elevational view thereof;

FIG. 5 is a sectional view taken along 5—5 of FIG. 1;

FIG. 6 is a sectional view taken along 6—6 of FIG. 1;

FIG. 7 is a perspective view thereof from the front right hand end and above, with the door ajar; and,

FIG. 8 is a perspective view corresponding to FIG. 7 but with coin entry and reject exit, and blanking plates added.

FIG. 1

FIG. 4

FIG. 5

FIG. 6

FIG. 2

FIG. 3

FIG. 8

FIG. 7
